UNITED STATES PATENT OFFICE

171,224

ELECTRIC WIRE SUSPENSION RACK

Henry C. Pfaff, Jr., Summit, N. J.

Application September 4, 1952, Serial No. 21,298

Term of patent 14 years

(Cl. D26—9)

To all whom it may concern:

Be it known that I, Henry C. Pfaff, Jr., a citizen of the United States, residing in Summit, Union County, New Jersey, have invented a new, original, and ornamental Design for an Electric Wire Suspension Rack, of which the following is a specification; reference being had to the accompanying drawing, forming a part hereof.

Fig. 1 is a top plan view of an electric wire suspension rack, embodying my new design,

Fig. 2 is a side elevational view thereof,

Fig. 3 is an end elevational view, taken on line 3—3 of Fig. 2, and

Fig. 4 is a transverse sectional view, taken on line 4—4 of Fig. 3.

I claim:

The ornamental design for an electric wire suspension rack, as shown.

HENRY C. PFAFF, JR.
